JOSEPH MAYER, OF SEATTLE, WASHINGTON, ASSIGNOR TO SEATTLE AERIE NO. 1,
FRATERNAL ORDER OF EAGLES, INC., OF SEATTLE, WASHINGTON, A CORPORATION
OF WASHINGTON

DESIGN FOR A BADGE

Application filed February 23, 1927. Serial No. 20,868. Term of patent 14 years.

To all whom it may concern:

Be it known that I, JOSEPH MAYER, a citizen of the United States, residing at Seattle, in the county of King and State of Washington, have invented a new, original, and ornamental Design for a Badge, of which the following is a specification, reference being had to the accompanying drawing, forming a part thereof.

I claim:

The ornamental design for a badge, as shown.

JOSEPH MAYER.
